H. F. EBERTS AND JOHN FANNING, OF DETROIT, MICHIGAN; SAID EBERTS
ASSIGNS HIS RIGHT TO SAID FANNING.

Letters Patent No. 97,285, dated November 30, 1869.

IMPROVED GAS-MACHINE FOR CARBURETTING AIR.

The Schedule referred to in these Letters Patent and making part of the same.

To whom it may concern:

Be it known that we, H. F. EBERTS and JOHN FANNING, of Detroit, in the county of Wayne, and State of Michigan, have invented a new and useful Improvement in Gas-Machines; and we do declare that the following is a true and accurate description thereof, reference being had to the accompanying drawings, and to the letters of reference marked thereon, and being a part of this specification.

The nature of this invention relates to an improved construction of a device for carburettting atmospheric air for illuminating-purposes; and consists in the peculiar arrangement in a vessel of a series of alternating shelves, said vessel being filled, to a line above the upper shelf, with gasoline or other hydrocarbon, and in the employment of a rotary pressure-blower, for forcing atmospheric air through the gasoline in tortuous currents between said shelves, thus enriching the air with the inflammable vapor evolved from the gasoline, and rendering it useful and valuable for illuminating-purposes.

In the drawings, which are a section of the carburettng-chamber and blower, and an' elevation of the other parts—

A represents a vessel or chamber, of wood or metal, and of any desired shape, provided at the top with an opening, *a*, for filling, and with the eduction-pipe *B*.

C is a series of shelves, placed in the vessel alternately on opposite sides thereof.

D is a rotary pressure-blower, of any approved pattern, rotated by a spur-wheel, E, engaging with a pinion on the end of the fan-shaft, which spur-wheel is intended to be operated by hand, being provided with a suitable crank for that purpose.

d is the blast-pipe of said blower, entering the carburettng-chamber A under the lowermost shelf.

F is a gasometer, of the usual pattern, into which the eduction-pipe B of the carburettor delivers the air-gas, and whence it is distributed to the burners through the gas-main *f*. The gas-holder is nearly counterbalanced by a weight, *g*, connected thereto by a cord, *h*, passing over proper sheaves *i* in the frame-work, at the top of the guide-standards *j*.

The operation of the device is as follows:

The carburettng-chamber A is filled with gasoline, or other liquid hydrocarbon, to a point above the shelves C, through the opening *a*, which is then tightly closed.

The blower D is then set in motion, which will force a current of air down the blast-pipe *d*, into the chamber A, under the lowermost shelf into the gasoline, through which it passes until it reaches the end of the shelf, and rising, it is deflected by the next shelf above, and compelled to travel in an opposite direction to its end, continuing its tortuous flow through the body of the liquid until it escapes at its surface in a myriad of bubbles, enriched with the inflammable vapor of the liquid evolved by its passage through it. The pressure being continued, it is forced through the eduction-pipe B, into the gas-holder F, which rises as it is filled, and from which it is conveyed, through the main *f*, to the burners.

The gas-holder being of sufficient capacity, a few minutes expended each day in rotating the blower, will suffice to fill the holder with enough air-gas to illuminate an ordinary dwelling-house until the next day.

An air-cock may be placed in the pipe B, if deemed necessary, so that should, at any time, the air-gas in the holder prove too rich for economical consumption, it may be opened, and by pulling down on the cord *h*, the holder will rise and draw in sufficient air through said cock to reduce the air-gas contained therein to the proper standard.

What we claim as our invention, and desire to secure by Letters Patent, is—

The combination of the carburettng-chamber A, provided with the shelves C and with the opening *a*, the blower D, the spur-wheel E, the blast-pipe *d*, the eduction-pipe B, provided with an air-cock, the gasometer F, provided with the main *f*, the standard *j*, the pulleys *i*, the cord *h*, and the weight *g*, when constructed, arranged, and operating as and for the purposes above set forth.

Also, in carburettng-chambers, providing the eduction-pipe with an air-cock, through which atmospheric air may be drawn by raising the gasometer, for the purpose of increasing the illuminating-power of the gas.

H. F. EBERTS.
JOHN FANNING.
